(57) **CLAIM**

The ornamental design for the lighted post, as shown and described.

DESCRIPTION

FIG. 1 is an elevation view of the lighted post of the present invention;

FIG. 2 is a top plan view of the lighted post of FIG. 1; FIG. 3 is a bottom plan view of the lighted post of FIG. 1; FIG. 4 is a left side elevation view of the lighted post of FIG. 1;

FIG. 5 is a right side elevation view of the lighted post of FIG. 1;

FIG. 6 is a back elevation view of the lighted post of FIG. 1;

FIG. 7 is a front, left side, right side, and back elevation view of another embodiment of the lighted post of the present invention;

FIG. 8 is a top plan view of the lighted post of FIG. 7;

FIG. 9 is a bottom plan view of the lighted post of FIG. 7; FIG. 10 is an elevation view of another embodiment of the lighted post of the present invention;

FIG. 11 is a top plan view of the lighted post of FIG. 10; FIG. 12 is a bottom plan view of the lighted post of FIG. 10; FIG. 13 is a right side elevation view of the lighted post of FIG. 10;

FIG. 14 is a back elevation view of the lighted post of FIG. 10;

FIG. 15 is a left side elevation view of the lighted post of FIG. 10;

FIG. 16 is an elevation view of another embodiment of the lighted post of the present invention;

FIG. 17 is a top plan view of the lighted post of FIG. 16;

FIG. 18 is a bottom plan view of the lighted post of FIG. 16; FIG. 19 is a right side elevation view of the lighted post of FIG. 16;

FIG. 20 is a left side elevation view of the lighted post of FIG. 16;

FIG. 21 is a back elevation view of the lighted post of FIG. 16;

FIG. 22 is an elevation view of another embodiment of the lighted post of the present invention;

FIG. 23 is a top plan view of the lighted post of FIG. 22;

FIG. 24 is a bottom plan view of the lighted post of FIG. 22; FIG. 25 is a left side elevation view of the lighted post of FIG. 22;

FIG. 26 is a right side elevation view of the lighted post of FIG. 22;

FIG. 27 is a back elevation view of the lighted post of FIG. 22;

FIG. 28 is a front, left side, right side, and back elevation view of another embodiment of the lighted post of the present invention;

FIG. 29 is a top plan view of the lighted post of FIG. 28; FIG. 30 is a bottom plan view of the lighted post of FIG. 28; FIG. 31 is an elevation view of another embodiment of the lighted post of the present invention;

FIG. 32 is a top plan view of the lighted post of FIG. 31; FIG. 33 is a bottom plan view of the lighted post of FIG. 31; FIG. 34 is a right side elevation view of the lighted post of FIG. 31;

FIG. 35 is a back elevation view of the lighted post of FIG. 31;

FIG. 36 is a left side elevation view of the lighted post of FIG. 31;

FIG. 37 is an elevation view of another embodiment of the lighted post of the present invention;

FIG. 38 is a top plan view of the lighted post of FIG. 37;

FIG. 39 is a bottom plan view of the lighted post of FIG. 37;

FIG. 40 is a right side elevation view of the lighted post of FIG. 37;

FIG. 41 is a left side elevation view of the lighted post of FIG. 37; and,

FIG. 42 is a back elevation view of the lighted post of FIG. 37.
